[57] CLAIM

The ornamental design for a dispensing container for liquid adhesive or the like, substantially as shown and described.

DESCRIPTION

FIG. 1 is a left side elevational view of a dispensing container for liquid adhesive or the like, with the cap closed, showing my new design;

FIG. 2 is a front elevational view thereof;

FIG. 3 is a back elevational view thereof;

FIG. 4 is a top plan view thereof;

FIG. 5 is a bottom plan view thereof; and

FIG. 6 is a front and right side perspective view thereof with the cap removed.

FIG. 1

FIG. 2

FIG. 4

FIG. 5

FIG. 3

FIG. 6
